DESIGN FOR A STOVE.

Design No. 12,607, dated December 20, 1881.

Cut 251.

UNITED STATES PATENT OFFICE.

H. CLAY BASCOM AND CYRUS A. HODGES, OF TROY, N. Y., ASSIGNORS TO N. S. VEDDER PATTERN WORKS, BASCOM, GALBRAITH & CO., OF SAME PLACE.

DESIGN FOR A STOVE.

SPECIFICATION forming part of Design No. 12,607, dated December 20, 1881.

Application filed November 18, 1881. Term of patent 7 years.

To all whom it may concern:

Be it known that we, H. CLAY BASCOM and CYRUS A. HODGES, each a citizen of the United States, residing in the city of Troy, in the county of Rensselaer and State of New York, have 5 jointly invented and produced a new and original ornamental Design for a Stove, of which the following is a specification, reference being had to the accompanying cut, print, or engraving of a stove having our said new design.

The design for the top consists of the oblong dome-form plate A, having the outer border series of upwardly-pointing alternate broad and narrow ornaments b, the top ornaments, 15 c, and the intermediate compound series of ornaments, d, composed of the several ornamental figures shown, and all shaped and arranged as represented in the aforesaid print.

The design for the front plate, B, consists 20 of the upper and lower series of alternate large and small pointed link-form ornaments, e f e f, the intermediate rectangular link ornaments, g, and the connecting ornaments h h', extending along the outer edges of said plate, in combination with the contiguous inner series of compound angular fillets, i, and vine-form ornaments j, the whole shaped and arranged together as shown in the accompanying engraving.

30 The design for the middle upper front portion, C, consists of the combination of the upper projecting part, D, inclined outward and downward, and having the oblong check-draft door E, curved convexly, with the series of arch-top apertures a and ornaments a', the door F, curved convexly outward and downward, and having the arch-top mica lights k, intervening ornaments, and lower upright tablet and ornament, l, and the bottom upright part, G, 35 having the rectangular apertures m and ornaments n, all shaped and arranged as represented in the aforesaid cut.

The design for the door H consists of the rectangular panel o, having thereon the cen-

tral ornament composed of the fillet-border p, 45 curved as shown, and surrounding the flower-and-leaf ornament q, extending from the radiating corner ornament, r, and the border composed of the corner ornaments, t, and intermediate series of ornaments, s, all shaped and arranged as represented in the aforesaid print. 50

The design for the door I consists of the swelled panel J, having thereon the central ornament, K, composed of the curved fillet-border u, inclosing the plant ornament v, having pinnate leaves w, and extending from the radial corner ornament, x, and the outer panel border, composed of the series of side ornaments, y, and corner ornaments, z, all shaped and arranged substantially as shown in the 60 aforesaid engraving. 55

What we claim as our joint invention is—

1. The design for the top, consisting of the oblong dome-form plate A, having thereon the compound ornamentations b, c, and d, all composed, shaped, and arranged as set forth. 65

2. The design for the front plate, B, consisting of the series of ornaments e f e f g h h' i j, all shaped and arranged together as set forth.

3. The design for the middle upper front 70 portion, C, consisting of the combination of the parts D E a a' F k l and G m m, all shaped and arranged together as set forth.

4. The design for the door H, composed of the parts o p q r s t, all shaped and arranged 75 as shown and described.

5. The design for the door I, consisting of the parts J K u v w x y z, all shaped and arranged as set forth.

In testimony whereof we hereunto set our 80 hands, in the presence of two subscribing witnesses, this 16th day of November, 1881.

H. CLAY BASCOM.
CYRUS A. HODGES.

Witnesses:

AUSTIN F. PARKE,
JAMES T. GOODFELLOW.
